UNITED STATES PATENT OFFICE.

FERDINAND ROCHOW, OF BROOKLYN, NEW YORK.

BALANCED SLIDE-VALVE.

SPECIFICATION forming part of Letters Patent No. 270,986, dated January 23, 1883.

Application filed June 15, 1882. (No model.)

To all whom it may concern:

Be it known that I, FERDINAND ROCHOW, of Brooklyn, in the county of Kings and State of New York, have invented a new and Improved Balanced Slide-Valve, of which the following is a specification.

Figure 1 is a vertical central section of my improved slide-valve. Fig. 2 is a bottom view of same. Fig. 3 is a top view of the spring-rings used therein; Fig. 4, a bottom view of the plates that are placed on top of said valve.

This invention relates to a new construction of slide-valve, which is adapted to receive steam either through the usual exhaust-port or through a separate or outer supply—that is to say, either on the inner or on the outer side of the valve.

The invention is more particularly intended to be used in connection with the reversible engine described in the application for a patent filed by me March 16, 1882, and numbered 55,465.

It consists in the use, between two vertical sections of the valve, of two beveled spring-rings, one applied to the outer, the other to the inner, side of the said sections, so that the valve will be made tight-fitting by that one of the rings which is in contact with the steam-supply.

In the arrangement of parts described in my aforesaid application it appears essential that the slide-valves in the steam-chests should be of such a character as to allow the steam to enter either within the hollow of the slide-valves or on the outside of the valves. To this end the particular construction of slide-valve which is shown in Figs. 1, 2, 3, and 4 is most desirable, said slide-valves being so arranged that when the piston of the corresponding cylinder is at the end of the stroke the valve is in the middle of its position, covering all the ports, as shown in Fig. 1, which figure shows a sectional view of the steam-chest F and slide-valve I therein contained. The

slide-valve I is made in two parts, a and b, both of circular form, excepting at the lower end of a, which is rectangular. The lower part, a, rests on the cylinder-face, and has lips or lower faces that enable it to close the ports m and n. The upper part, b, of the slide-valve is also circular, and of about the size, horizon-

tally considered, of the part a, and has cast or otherwise secured onto it an inner cross or guide piece, d, that enters into the part a and keeps the parts a and b at all times properly aligned. In the top of the steam-chest and on top of the slide-valve are two wedge-shaped plates, e and f, the lower of which is suspended by screws g, while the upper can be adjusted by a horizontal screw, h. The lower edge of the part b is circular when looked at from below, and so is the upper edge of the part a when seen from above, and these edges are V-shaped, vertically considered, as shown in Fig. 1. Between these V-shaped edges of the parts a and b are interposed the two spring-rings i and j. The inner ring, i, bears against the inner tapers of the V-shaped edges of the parts a and b, while the outer ring, j, bears against the outer tapers of said edges, all as clearly shown in Fig. 1. Now, it is evident that when steam is admitted to the inner part of the valve I—say through the port o—it will expand within the valve I and press the inner spring-ring, i, outward, causing the same to press in turn against the inclined inner contact-edges of the parts a and b, spreading them apart, thus tightening the valve against the lower and upper faces. Again, when steam is admitted to the steam-chest F outside of the valve I its pressure is exerted on the outer ring, j, which in like manner will cause the parts a and b to be spread apart, thus under all circumstances insuring a tight fit of the valve against the surfaces between which it moves. By the screws g and h the distance between the upper and lower contact-surfaces of the valve can always be regulated as circumstances may require.

It has always been a difficult problem to produce a thoroughly practical slide-valve which will keep completely steam-tight, no matter whether the steam enters inside of the valve or outside, and which will by its own wear and tear tend to remain steam-tight, and which, also, will not be liable to stick and rest its parts together, and does not depend upon the action of any springs alone. I believe that the valve described by me overcomes all these difficulties. The elasticity of the rings i and j is utilized only under pressure of the steam, and not otherwise. In fact, my valve is self-

adjusting, and will keep tight after considerable wear of surfaces; yet by means of the screws *g* and *h* and adjustable back plate, *e*, means are furnished to compensate any wear caused by the motions of the valve.

5 I claim—

1. The slide-valve I, composed of the lower section, *a*, having V-shaped upper edge, of the upper guided section, *b*, having V-shaped lower edge, and of the inner spring-ring, *i*, and outer spring-ring, *j*, placed against the inner and

outer bevels of said sections, respectively, substantially as herein shown and described.

2. The combination of the section *a* with the section *b*, guide-cross *d*, inner spring-ring, *i*, and outer spring-ring, *j*, substantially as herein shown and described. 15

FERDINAND ROCHOW.
